(57) CLAIM

The ornamental design for a disposable bag with a collar, as shown and described.

DESCRIPTION

FIG. 1 is a top view of the disposable bag with a collar; FIG. 2 is a bottom view thereof; FIG. 3 is a front view thereof; and, FIG. 4 is a right side view thereof; the left side view being a mirror image thereof.

The broken lines shown in Figures illustrate portions of the disposable bag with a collar that form no part of the claimed design.
